UNITED STATES PATENT OFFICE

WILLIAM SHAKESPEARE, JR., AND WILLIAM SCHMID, OF KALAMAZOO, MICHIGAN,
ASSIGNORS TO SHAKESPEARE COMPANY, OF KALAMAZOO, MICHIGAN.

AIR-HEATER FOR CARBURETERS.

1,226,710.

Specification of Letters Patent.

Patented May 22, 1917.

Application filed March 17, 1916. Serial No. 34,853.

To all whom it may concern:

Be it known that we, WILLIAM SHAKESPEARE, Jr., and WILLIAM SCHMID, citizens of the United States, residing in the city 5 and county of Kalamazoo, State of Michigan, have invented certain new and useful Improvements in Air-Heaters for Carbureters, of which the following is a specification.

10 This invention relates to improvements in air heaters for carbureters.

The main objects of this invention are to provide an improved air heater for carbureters which may be conveniently applied 15 to the exhaust pipe of an internal combustion engine in the desired position thereon and one to which the air conduit of the air carbureter is conveniently connected.

Further objects, and objects relating to 20 structural details, will definitely appear from the detailed description to follow.

We accomplish the objects of our invention by the devices and means described in the following specification. The invention 25 is clearly defined and pointed out in the claims.

A structure which is a preferred embodiment of our invention is clearly illustrated in the accompanying drawing forming a 30 part of this specification, in which:

Figure I is a side view of the structure embodying the features of our invention, the parts being shown mainly in conventional form.

35 Fig. II is an enlarged detail section on a line corresponding to line 2—2 of Fig. I.

Fig. III is an inside perspective view.

In the drawings similar reference numerals refer to similar parts throughout the 40 several views.

Referring to the drawing, 1 represents an internal combustion engine, 2 the exhaust pipe thereof, 3 the carbureter and 4 the hot air conduit of the carbureter. These 45 parts are all shown in conventional form as their structural details form no part of our present invention.

Our improved hood, designated generally by the numeral 5, has curved side walls 6 50 and end walls 7, the end walls having V-shaped recesses 8 therein adapted to receive the pipe 2, as shown in Fig. II. The hood 5 is provided with an attaching collar 9 for the conduit 4, the side wall of the hood 55 has a slot-like opening 10 at one side and

a shouldered offset 11 on the opposite side, the offset having a slot 12 in its top. A pin 13 is disposed adjacent the opening 10 so that it projects into the collar 9 constituting a locating stop for the conduit 4. The 60 collar is perforated to receive the pin 14, the perforations in the collar and conduit being disposed so that they register when the conduit abuts the pin 13.

The clamping or retaining strap 15 is 65 provided with a series of perforations 16 at one end, its perforated end being arranged through the opening 10 engaged with the pin 13 which is disposed adjacent thereto. The hood is provided with a boss 70 17 to properly support the strap in engagement with the pin. At its other end the strap 15 is provided with a loop 18 having a perforation 19 in its bight to receive the clamping bolt 20 which is arranged through 75 the slot 12 in the offset.

The nut 21 is arranged in a loop of the strap to coact with the bolt, the head of which is slotted to receive a screw driver so that by turning the bolt the strap may 80 be tightened or clamped upon the exhaust pipe. This provides a very convenient and secure means for attaching the hood to the pipe and one which permits its being attached in positions which are not conveniently accessible and would preclude the possibility of attaching hoods by the means 85 ordinarily employed.

Having thus described our invention, what we claim as new and desire to secure 90 by Letters Patent, is:

1. In a structure of the class described, the combination of a hood having a curved side wall and end walls having V-shaped recesses adapted to receive a pipe, the side 95 wall having an attaching collar for an air conduit and a slotted offset at one side of said collar and an opening at the other side, a pin disposed adjacent said opening, a strap having a series of pin engaging perforations at one end disposed through said side wall opening and engaged with said pin, the other end of the said strap being provided with a loop having a perforation therein, and a bolt disposed through said 100 slot in said hood offset and said perforation in said strap loop, there being a nut disposed within said loop to coact with said bolt.

2. In a structure of the class described, 110

the combination of a hood adapted to embrace the side of a pipe and having a conduit attaching collar and an offset at one side and an opening at the other, a pin disposed adjacent said opening, a strap having a series of pin engaging perforations at one end disposed through said wall opening and engaged with said pin, the other end of the said strap being provided with a loop having a perforation therein, and a bolt disposed through said offset and said perforation in said strap loop, there being a nut disposed within said loop to coact with said bolt.

15 3. In a structure of the class described, the combination of a hood adapted to embrace the side of a pipe and having an opening at one side and a pin disposed adjacent said opening, a strap having a perforation at one end disposed through said opening and engaged with said pin, the other end of the said strap being provided with a loop having a perforation therein, and a bolt disposed through said hood and said 20 perforation in said strap loop, there being a nut disposed within said loop to coact with said bolt.

4. In a structure of the class described, the combination of a hood having a side 30 wall and end walls recessed to receive an exhaust pipe, the side wall having an attaching collar for an air conduit and an offset at one side of said collar and an opening at the other side, a pin disposed adjacent 35 said opening, a strap having a series of pin engaging perforations at one end disposed through said side wall opening and engaged with said pin, the other end of said strap being provided with a nut and a bolt disposed through said offset to engage said 40 nut.

5. In a structure of the class described, the combination of a hood adapted to embrace the side of a pipe and having an opening at one side and a pin disposed adjacent 45 said opening, a strap having a series of pin engaging perforations at one end disposed through said opening and engaged with said pin, and a bolt carried by said hood and 50 operatively connected to the other end of said strap for clamping the strap upon the pipe.

6. In a structure of the class described, the combination of a hood adapted to 55 embrace the side of a pipe and provided with a strap pin at one side, a strap having pin engaging perforations at one end engaging with said pin, and a bolt carried by said hood and operatively connected to the other end 60 of said strap for clamping the strap on the pipe.

7. In a structure of the class described, the combination with the exhaust pipe of an

internal combustion engine and a carburetor air conduit, of a hood adapted to embrace 65 the side of the exhaust pipe and having an attaching collar for the air conduit and an offset at one side and an opening at the other side, a pin disposed adjacent said opening, a strap having a pin engaging perforation at one end disposed through said opening and engaged with said pin, and a bolt disposed through said offset to coact with the other end of said strap for clamping the strap upon the pipe. 75

8. In a structure of the class described, the combination with the exhaust pipe of an internal combustion engine and carburetor air conduit, of a hood adapted to embrace the side of the exhaust pipe and having an 80 attaching collar for the air conduit and an opening at one side, a pin disposed adjacent said opening and projecting on the inside of the collar constituting a locating stop for the air conduit, a strap having a 85 perforation at one end disposed through said opening and engaged with said pin, and a bolt disposed through said hood and operatively connected to said strap for clamping it upon the pipe. 90

9. In a structure of the class described, the combination with the exhaust pipe of an internal combustion engine and a carburetor air conduit, of a hood adapted to embrace the side of the exhaust pipe and 95 having an attaching collar for the air conduit and an opening at one side, a pin disposed adjacent said opening, a strap having a perforation at one end disposed through said opening and engaged with said pin, 100 and a bolt disposed through said hood and operatively connected to said strap for clamping it upon the pipe.

10. In a structure of the class described, the combination with the exhaust pipe of 105 an internal combustion engine and a carburetor air conduit, of a hood adapted to embrace the side of the exhaust pipe and adapted to receive the air conduit and having an opening at one side and a pin adjacent 110 said opening, a strap having pin engaging perforations at one end disposed through said opening and engaged with said pin, and a bolt disposed through said hood and operatively connected to the other end 115 of said strap for clamping the strap upon the pipe.

In witness whereof, we have hereunto set our hands and seals in the presence of two witnesses.
